UNITED STATES PATENT OFFICE.

HARVEY A. DIXON, OF PORT HURON, MICHIGAN.

DESIGN FOR A BODY FOR CHILDREN'S CARRIAGES.

SPECIFICATION forming part of Design No. 28,318, dated February 22, 1898.

Application filed June 21, 1897. Serial No. 641,719. Term of patent 7 years.

all whom it may concern:

Be it known that I, HARVEY A. DIXON, a citizen of the United States, residing at the city of Port Huron, in the county of St. Clair, State of Michigan, have invented and produced a new and original Design for Bodies for Children's Carriages or Push-Carts, of which the following is a specification, reference being had to the accompanying drawing. In the drawing is shown a perspective view of a body for a child's carriage or push-cart embodying my design.

As shown in the drawing, the leading or essential feature of the design is the configuration or form of the body, comprising the at-supporting or push frame, consisting of a gracefully-curved substantially ogee side-bars *b b*, extending from their lowermost ends a generally rearward and upward direction, constitute the handle or push bars of the carriage-frame, and the springs *c c*, one extending from the under side of the lower por-

tion of each side-bar *b* backward in a long compound curve and having its rear end bent or curved to form a large loop *c'*, pass over, 25 back of, and under the rear axle *e*, to which latter it is attached. Connecting the side-bars *b b* at their forward ends is a cross plate or bar *g*, forming a foot-rest. Between the side-bars *b b*, above the foot-rest, is a seat *d*, 30 provided, preferably, with arm and back rests.

On each side of the frame is a gracefully-curved fender or mud-guard *f* for the wheels.

h is the forward axle, crossing the frame at its lower end and secured to the side-bars *b b*. 35

What I claim as new, and desire to secure by Letters Patent, is—

The design for a body for a child's carriage or push-cart, substantially as shown and described.

HARVEY A. DIXON.
